UNITED STATES PATENT OFFICE

121,337

DESIGN FOR A DOOR SUITABLE FOR OVENS OR THE LIKE

Clarence Karstadt, Glen Ellyn, Ill., assignor to
Sears, Roebuck and Co., Chicago, Ill., a corpora-
tion of New York

Application August 4, 1939, Serial No. 86,460

Term of patent 3½ years

To all whom it may concern:

Be it known that I, Clarence Karstadt, a citizen of the United States, residing at Glen Ellyn, in the county of Du Page and State of Illinois, have invented a new, original, and ornamental Design for a Door Suitable for Ovens or the Like, of which the following is a specification, reference being had to the accompanying drawing, forming a part thereof.

Fig. 1 is a front elevation of a door suitable for ovens or the like embodying my new design.

Fig. 2 is a top plan view of the same.

Fig. 3 is an end elevation of the same.

The characteristic features of my design lie in the front ornamentation in combination with the specific oven door shown.

I claim:

The ornamental design for a door suitable for ovens or the like, substantially as shown and described.

CLARENCE KARSTADT.
